UNITED STATES PATENT OFFICE

2,315,604

SEAL FOR WASHING MACHINES OR THE
LIKE

Edward A. Ebert, Buffalo, N. Y., assignor to Chicago Electric Manufacturing Company, Chicago, Ill., a corporation of Illinois

Original application November 19, 1938, Serial No. 241,357. Divided and this application July 3, 1940, Serial No. 343,692

3 Claims. (Cl. 68—132)

The present invention relates to a seal for a washing machine or the like and more particularly to a seal for a device or container in which there is employed an agitator or like element.

The present invention is specifically concerned with the provision of a portable washing machine which occupies a relatively small space both during use and during storage.

This application is a division of my co-pending application, Serial No. 241,357, filed November 19, 1938, for an improvement in a Washing machine.

An object of the present invention is to provide in a washing machine or the like, comprising only three parts, which parts are readily assembled and freely separable for cleaning, handling, and arrangement in storage, a resilient frictional engaging means between the part mounting the driving members and the supporting means for the said part such that no special interconnection or clamping means is necessary, while at the same time loss of washing fluid due to agitation or splashing is prevented.

A further object of the invention is to provide means for so supporting a container cover for a washing machine or the like on the container that the forces set up by a driving mechanism carried by the cover and interacting with means in the container will be effectively resisted without latching means so that such mechanism cannot cause relative movement between the cover and the container.

Numerous other objects and advantages will be apparent throughout the course and progress of the following specification wherein:

Fig. 1 is an elevational view of a washing machine constructed in accordance with the present invention, the lower portions having been broken away along a line extending centrally through the machine in order to disclose the internal structure;

Fig. 2 is a sectional detail view taken on the line 2—2 in Fig. 1;

Fig. 3 is a sectional detail view taken on the line 3—3 in Fig. 1;

Fig. 4 is a sectional detail view taken on the line 4—4 in Fig. 1;

Fig. 5 is a sectional view taken through the machine on the line 5—5 in Fig. 1;

Fig. 6 is a sectional detail view taken on the line 6—6 in Fig. 1;

Fig. 7 is a sectional detail view taken on the line 7—7 in Fig. 5, namely, on a plane which is normal to the plane upon which the section of Fig. 6 is shown.

The washing machine shown for the purpose of illustrating the present invention comprises in general a cylindrical vessel 10 for enclosing the wash, an agitator 12 normally arranged within the vessel but removable therefrom, as will hereinafter appear more in detail, and a cover and

drive assembly 14. The enclosing vessel 10 is defined by an upstanding cylindrical side wall 16 closed at its lower end by the bottom wall 18, the upper end of the container per se being open, as clearly shown in Fig. 1. It should be noted that the upper edge of the cylindrical wall 16 is flanged outwardly as at 20 to provide an annular, upwardly facing recess adapted to receive and support the lower edge of the cover member (Fig. 1). The annular flange 20 terminates radially in an annular, rounded bead 22. Handle members 24 oppositely positioned on the outer upper surface of the vessel 10 are permanently riveted to the vessel through the agency of rivets 26.

15 The bottom wall 18 mounts centrally thereof a pivot pin or pintle 28. It will be obvious from a consideration of Fig. 1 that the pin 28 is secured in place by passing its reduced lower cylindrical end 30 through a close-fitting aperture in the bottom wall 18 and heading over the projecting portion as at 32. A washer 34 is preferably included in the assembly, as shown in the figure, to provide a thrust bearing surface for the agitator. It will be obvious from the above that the pintle assembly 20 shown provides a positive, permanent interconnection free from any possibility of leakage or failure.

20 The agitator 12 is formed with a central cylindrical column 36 comprising a tube provided with an integral plurality of radially projecting vanes 38, having adjacent its lower end an outwardly projecting flange 40 radially co-extensive with the vanes. Attention is directed to the fact that the internal configuration of the tubular, central cylindrical column 36 is such as to properly engage the pivot pin 28 in bearing relationship, that is to say, when the agitator 12 is positioned upon the pin as shown in Fig. 1 it is pivotally mounted thereon for rotational or oscillatory movement 25 while being positioned centrally with respect to the washing container. It should be noted that the lower end of the column 36 rests in bearing relationship upon the washer 34, the lower inner edge of the column being beveled or chamfered as at 42 to enhance this function. The upper end of the tubular column portion 36 of the agitator is configurated internally as at 44 (Figs. 1 and 6) for the purpose of accommodating a rectangular driving member. That is to say, while the central tubular portion of the agitator is cylindrical in the embodiment shown, the upper end provides in axial alignment therewith an aperture of polygonal cross section. The motive driving and transmission means for the entire machine is comprised 30 by the top unit 14 which comprises a circular, somewhat bell-shaped cover 46. It should be noted that the cover is flanged downwardly adjacent its periphery as at 48 and terminates in a rolled or curved bead 50, the bead 50 serving to mount an annular tubular supporting member 52.

which seats within the annular recess provided by the flange 20, as hereinbefore described.

It is of great importance to note that the annular supporting member 52 is preferably of some suitable frictional material, preferably having resilient characteristics, adapted to make firm frictional contact with the supporting vessel 10. This is of great importance, not only in preventing splashing or leakage of the washing fluid but also because the parts in operation must necessarily at all times be interengaged sufficiently to resist the reactive forces set up by the actuation of the agitator. Thus, in accordance with the preferred embodiment of the present invention the interengaging portions of the cover and body portion of the washer are preferably free from special interconnecting means, being symmetrically, annularly formed so that they may be instantly assembled by any unskilled person without the necessity of positive mechanical interconnection. It has been found, however, in accordance with the present invention, that the parts are adequately engaged and supported when the annular supporting member 52 is composed of rubber, leather or the like. The instant structure, moreover, assures the proper interengagement of the parts without regard to close tolerances in manufacture.

The cover unit 14 mounts centrally thereof a driving motor 54 and a transmission assembly 56. The motor, in the embodiment disclosed, has a handle 58 across its upper end which greatly facilitates the manipulation of the entire cover unit. The motor is mounted on the cover in axial alinement with the agitator, having a drive shaft projecting downwardly as at 60 (Figs. 6 and 7). The present motor 54 is provided with a lower, self-aligning bearing structure. To this end the lower wall 62 of the motor housing is formed downwardly or convexly as at 64 and terminates in an annular, inclined flange portion 66 adapted to engage a bulged or generally spherical portion of the bearing 68 formed on the shaft. A separate sheet member or plate 70, apertured upwardly to provide an inclined flange bearing support 72, engages the upper part of the spherical section 68 and is held in position by tab or finger portions 74 extending through opposed slots 76 in the lower wall 62 of the motor. The motor 54 rests upon four upwardly, convexly deformed landings 78, being secured rigidly to the cover by means of machine bolts and nuts 80 and 82. It should be noted that the lower wall 62 of the motor housing is apertured as at 84 to provide for ventilation, the top wall being preferably apertured in the same manner. In making the apertures 76 the material removed is struck out as at 86 for positioning the nuts 82.

The transmission assembly comprises a housing 88 closed by an integral wall 90 at its bottom and by a separable wall 92 at the top. A plurality of elongated embossments 94 project upwardly from the top wall 92 and extend into the concavities formed by the deformations 78 to properly space the housing from the cover, the aforementioned machine bolts 80 extending through the housing and the embossments 94 to rigidly unite the transmission, the cover and the motor.

The cover 92 is additionally provided with an upstanding cylindrical skirt 96 which encloses the shaft 60 and performs the important

function of sealing the motor bearing with the cooperation of a sealing washer 98. Thus, the sealing washer 98 is clamped between the upper annular edge of the skirt 96 and lower portion 5 of the motor housing, the cover 46 being apertured sufficiently to permit a portion at least of the washer to extend freely therethrough. Attention is particularly directed to the fact that arranged and assembled in the manner shown in Figs. 6 and 7 it is impossible for the sealing washer to become dislocated in any direction.

The present transmission assembly is arranged to transform the rotational energy of the drive motor preferably into oscillatory reduced motion for transmission to the agitator. For this purpose, the lower end of the drive shaft 60 is provided with a small pinion 100, rigid therewith, which meshes with a larger gear 102. The gear 102 carries in axial alinement a pinion 104 which, in turn, meshes with a spur gear 106. The spur gear 106 has a cylindrical pivot 108 providing a crank, the crank 108 pivotally mounting the end of a rack 110 through the agency of a bearing sleeve or bushing 112. The teeth of the rack member 110 engage a pinion 114 rigidly pinned as at 116 to a drive shaft 118 (Figs. 6 and 7). The rack 110 is maintained in engagement with the pinion 114 at all times by means of a pin 115 rigid with the bottom wall 90 of the housing and engaging the rear side of the rack. Accordingly, in operation, rotation of the motor shaft 60 rotates the crank 108 through the medium of the gears 100, 102, 104 and 106. The action of the crank 108, accordingly reciprocates the rack 110 to cause an oscillatory movement of the shaft 118. Attention is particularly directed to the fact that in accordance with the present structure the rack 110 slides on the bottom wall 90 of the housing. The bushing or fitting 112 has an upper flange which supports the gear 106. That is to say, the gear 106 is rigid with a supporting shaft 120 which is rotatably seated within a receiving recess in the housing, the gear and its shaft being retained in the axial alinement clearly shown in Fig. 6 after the housing is assembled. The gear 102 is similarly mounted on the shaft 122 journalled in a similar bearing housing and is prevented from moving axially downwardly by means of a thrust washer 124 (Fig. 7), an edge of which engages above the large gear 106 so that the associated assembly is slidably supported thereon. It will be noted that the present arrangement permits rapid assembly in that the several gears may merely be slid into the relative positions shown and the top cover applied to the housing to retain the parts in operative position. It is contemplated that the housing be provided with a suitable lubricant, and, accordingly, a washer or seal 126 is located between the adjoining edges of the top and the main body of the housing. It will be obvious from the above that the application of the machine screws in the relationship shown not only interconnects the transmission, the motor and the cover, but clamps the entire transmission and its housing together as a unit.

The transmission drive or impeller shaft 118 extends downwardly into an adaptor or fitting 128, being secured thereto by pin 130. The fitting 128 has a cup-shaped configuration at its upper end to receive a grease sealing washer 132. Since the shaft 118 extends through the bottom wall of the transmission housing the seal 132 performs a necessary and important function in

preventing the influx of foreign matter into the interior of the washing vessel.

The lower end of the fitting 128 has a polygonal sectional configuration corresponding to the configuration of the aforementioned recess or aperture in the upper end of the agitator and is of such a length that it completely engages in driving relationship with the agitator when the parts are assembled as shown in Fig. 1.

From the foregoing it will be apparent that in operation the agitator is rotatably mounted upon the pin 28, after which the top unit is placed in position upon the upper edge of the washing vessel, at which time the end of the fitting 128 enters into the polygonal aperture in the agitator. In use, the washing vessel will first be supplied with a mass of wash and a body of washing fluid so that when the top unit is assembled the washing operation may be commenced by merely supplying the motor 54 with electric current by means of a suitable electric conduit (not shown). Operation of the motor produces a desired oscillatory movement of the agitator 12, which continues throughout the period of the washing operation.

The present invention provides a structure which is simple, compact and efficient. The washing vessel is extremely light and may be positioned at any convenient point and readily filled, emptied, and cleaned. So too, the agitator is freely removable from its supporting pin, and when in disuse the agitator may be removed from the assembly so that the washing container may be employed for storage purposes.

So also, in accordance with the present invention, there is provided a drive motor which is capable of being adequately ventilated, the motor, as pointed out above, being spaced from the cover a short distance to permit circulating air to enter the lower ventilating apertures 84, as indicated by the arrows in Fig. 6, and to pass out through the upper apertures.

It is unnecessary, according to the present invention, to especially arrange the top cover unit or to actuate a special fastening means to retain it in place. The reaction forces set up by the movements of the agitating element in the washing medium and which forces tend to cause rotation of the mechanism carrying cover relative to the container are effectively resisted without such fastening means. Hence assembly of the machine for use is simplified, its operation rendered more silent, and possibility of splashing eliminated.

It is thought that the invention and numerous of its attendant advantages will be understood from the foregoing description and it is obvious that numerous changes may be made in the form, construction and arrangement of the several parts without departing from the spirit or scope of the invention or sacrificing any of its attendant advantages, the form herein described being a preferred embodiment for the purpose of illustrating the invention.

I claim:

1. In a washing machine of the type comprising an upstanding, cylindrical vessel having an annular upper rim, a cover for said vessel, and an electric driving motor and transmission mechanism mounted thereon for driving an agitator within the vessel, said cover being free from mechanical interconnection with said vessel and completely bodily removable therefrom, said

cover having an annular, outer margin adapted to rest upon the upper rim of the vessel, and means for preventing displacement of the cover with respect to the vessel by the reactionary forces set up by the agitator when the cover is disposed in operative position on the vessel and the agitator is driven by the motor through the transmission mechanism, said means comprising an annular member of resilient frictional material embracing and gripping said margin of the cover, the frictional material on the under side of the cover being wedged between the cover and the rim of the vessel when the cover is disposed in operative position on the vessel, said wedged part of the resilient, frictional material frictionally fixing the cover to the vessel against displacement by said reactionary forces and sealing the cover to the vessel against loss of washing fluid therebetween.

2. In a washing machine of the type comprising an upstanding, cylindrical vessel having an annular upper, laterally extending rim portion, a cover for said vessel, and an electric motor and transmission mechanism mounted on said cover for driving an agitator within the vessel, said cover being free from mechanical interconnection with said vessel and completely bodily removable therefrom, said cover having an annular rim portion adapted to overlie the laterally extending upper rim portion of the cover, and means for preventing angular displacement of the cover with respect to the vessel by the reactionary forces set up by the agitator, one of said rim portions having an annular recess defined by walls converging in a direction away from the other of said rim portions, the other of said rim portions comprising an annular bead positioned for reception in said annular recess, said means comprising an annular strip of resilient, frictional material embracing and gripping said bead and being wedged within said converging walls of said recess to frictionally fix the cover to the vessel against displacement by said reactionary forces and seal the cover to the vessel against loss of washing fluid therebetween.

3. In a washing machine of the type comprising an upstanding, cylindrical vessel having an upper rim, a cover for said vessel, an electric driving motor and transmission mechanism mounted on said cover for driving an agitator disposed within, and co-axially of, the vessel, said cover being free from mechanical interconnection with said vessel and completely bodily removable therefrom, said cover having a rim portion provided with an annularly disposed and downwardly extending surface inclined with respect to the axis of the vessel, and means for preventing angular displacement of the cover with respect to the vessel by the reactionary forces set up by the agitator, said vessel having at said rim an annular surface complementary to said inclined surface of the cover, said means comprising an annular rubber member embracing and gripping the rim portion of the cover and wedged between the inclined surface of the cover and the complementary surface of the vessel when the cover is positioned on the vessel to frictionally fix the cover against angular displacement relative to the vessel by said forces and to seal the cover to the vessel against loss of washing fluid therebetween.
